UNITED STATES PATENT OFFICE.

ABELARDO HERBERT, OF LIMA, PERU, ASSIGNOR, BY DIRECT AND MESNE ASSIGNMENTS, OF TWENTY-FIVE ONE-HUNDREDTHS TO TEODOMIRO DE LOS HEROS Y JACOME AND THIRTY-SEVEN AND ONE-HALF ONE-HUNDREDTHS TO TERESA HANDLEY, BOTH OF LIMA, PERU.

GRAPHOPHONE.

1,332,723.

Specification of Letters Patent.

Patented Mar. 2, 1920.

Application filed December 31, 1918. Serial No. 269,073.

To all whom it may concern:

- Be it known that I, ABELARDO HERBERT, of Lima, Peru, have invented certain new and useful Improvements in Graphophones; and
- 5 5 I do hereby declare the following to be a full, clear, and exact description of the invention, such as will enable others skilled in the art to which it appertains to make and use the same.
- 10 10 This invention relates to graphophones and particularly to mechanism associated with means for stopping the motor to effect the removal of the record from playing position on the rotating plate.
- 15 15 The object of my invention is the provision of a very simple device which will automatically raise the record above the motor spindle to disengage the two and allow the disk by the centrifugal action imparted
- 20 20 by the rotating plate to be thrown to one side and deposited in a receptacle, the device being actuated in synchronism with the application of the brake to the rotating plate.
- In the accompanying drawings, Figure 1
25 25 is a top plan view showing a portion of a graphophone equipped with my device. Fig. 2 is a view in side elevation of the tripping device, a portion of the record with its supporting plate being shown. Fig. 3 is
30 30 a detailed perspective view of the several elements forming the trip mechanism. Fig. 4 shows in detail the parts forming the latch for the sound box.
- For the purposes of illustration my invention
35 35 is shown applied to a graphophone of known form wherein is included a cabinet A, rotating plate B, swinging tone arm C, and a sound box D supported by a curved neck E. In graphophones of this type the
40 40 supporting neck E is pivotally secured to the outer end of the tone arm and is adapted to be turned so as to remove the needle from engagement with the record disk to permit the latter to be lifted from the plate and a
45 45 different record placed thereon. In the drawings I have shown a mechanism for automatically effecting the raising of the sound box and its needle from the record disk and holding it in such elevated position while
50 50 the record is being removed. The record disk is provided with a raised inclined portion 2 which is the terminal of the record groove. It will be seen that as the needle

of the sound box travels along this groove and up the inclined surface the neck E will 55 be turned about its pivot. To maintain the neck, and consequently the sound box, in this raised position I provide it with an arm 3 which forms part of a latching device, the complementary part being in the form of a 60 T-shaped lever 4. The shank of this lever is pivoted about midway its length, as at 5, to the tone arm and its branches form a bolt 6 which extends through apertures in keeper plates 8, 9, rigidly secured to the 65 outer end of the tone arm. A coiled spring 10 surrounds a portion of the bolt 6 and is spaced between the shank of the lever and the plate 9 so as to constantly force the bolt into the vertical plane of movement of the 70 arm 3. When the sound box is in working position on the disk the bolt will bear against the face of the arm 3 with the spring 10 under tension. As soon as the needle has reached the end of the record groove and has traveled up the inclined portion 2 the bolt 6 will through the action of the spring 10 be projected so as to lie in the path of the arm and the latter will be held down with the supporting neck E slightly raised and the 80 needle out of engagement with the disk. In order that the sound box may be placed in playing position the lever 4 must be rocked on its pivot to disengage the latching members. This is readily accomplished by pressure on a thumb piece 12. 85

In the position of the parts as described, with the sound box raised and held so by the latching device, the brake mechanism is free to come into action. The brake is of 90 the friction type and preferably comprises a finger 20 having a wedge-like portion 21 of rubber or other material which is adapted to engage the edge of the rotating plate. This finger is hinged for vertical movement 95 as at 22 to a supporting bracket 23 firmly attached to the tone arm by a collar 24, a spring 25 being connected to the bracket and the finger to control the play of the finger as it engages the plate. The bracket, the 100 brake finger and the tone arm are adapted to swing together. A spring tension device 26, one end of which is secured to the brake and the other connected with a regulating button 27, is effective to turn the brake and tone 105 arm, the brake into engagement with the

- rotating disk and the arm into initial position. The tension of this spring device is not sufficient to hamper the inward movement of the sound box over the record.
- 5 In the use of my improved device for throwing off the records it is necessary that the record disk be spaced at its periphery a slight distance from the supporting plate. For this purpose the plate B is provided with 10 a raised portion 30 which is of less diameter than the records to be supported on the plate, and this raised portion may be an integral part of the plate, or a mat of rubber or other composition may be employed. At one side 15 of the cabinet A, preferably that opposite the point of initial engagement of the sound box and disk, I provide an arm 31 pivotally secured at one end to upstanding ears 32, its free end being adapted to project into 20 the peripheral space between the record and the plate B. The arm 31 which is constantly urged upward by a spring 33, of any preferred form, is held down against the tension of this spring by a pivoted catch 34 at 25 one side of the arm. To the end of the longer arm 36 of a two arm lever 37, on a vertical pivot 38, is secured one end of a flexible member 39, the other end being connected with the catch 34 at a point slightly 30 higher than the point of connection with the lever. In the normal use of my improved throw-off device, the arm 36 lies across the arc described by the brake finger 20 in its movement to stop the rotating plate and in 35 this position the flexible member 39 is held taut between the catch 34 and the end of the lever arm. If it is desired to repeat a given record the throw-off device may be switched out of operative position by the shorter arm 40 of the lever 37.
- In operation, the arm 31 is pressed down against the tension of its spring and the catch 34 applied to hold it. A record is then placed on the plate, the lever 37 is 45 turned so that its arm 36 will lie across the arc described by the brake finger thereby bringing the flexible member into position to be drawn by the brake finger 20 to trip the catch 34 and release the arm 31. This 50 movement takes place about at the time the tone arm reaches a point where the needle is in vertical line with the edge of the rotating plate and before the brake has been brought to a position, by the swing of the tone arm 55 under the influence of its spring tension device 26, to check the rotation of the plate. As the arm 31 springs upwardly it will raise 60 the record sufficiently high to free it from engagement with the spindle of the motor and the edge of the record diametrically opposite the arm still being in contact with the rotating plate will receive the full force of this rotation and the centrifugal action will throw the record to one side and into contact 65 with a roller 40 at one side of the cabinet,
- the roller effecting easy conveyance of the record to a receptacle 41. I have shown an ordinary envelop 42 arranged on the receptacle to receive the record. The roller 40 has a central depression 43 so that the raised portion 2 on the under side of the record, where a double record is used, will not be damaged. A post 44 having an overturned end at one side of the trip arm serves the dual function of guiding the record to the 70 roller and of limiting the upward movement of the arm 31.
- I claim as my invention:
1. In combination with a graphophone having a rotating plate and a record thereon, a swinging tone arm, a sound box support pivotally mounted at the outer end of said arm, and means for automatically raising and holding said support, brake mechanism actuated by said tone arm, and means actuated by said brake mechanism for automatically removing said record from said rotating plate. 80
  2. In combination with a graphophone having a rotating plate and a record thereon, a swinging tone arm, a sound box support pivotally mounted at the outer end of said arm, and means for automatically raising and holding said support, brake mechanism actuated by said tone arm, and means actuated by said brake mechanism for partially lifting said record from the rotating plate to permit the centrifugal action of the plate to throw the record to one side. 90
  3. In combination with a graphophone having a rotating plate, a record thereon, a swinging tone arm, a sound box support pivotally mounted at the outer end of said arm, and means for automatically raising and holding said support, brake mechanism actuated by said tone arm, a spring actuated trip arm, means for holding said arm retracted, said trip being adapted to engage the record to partially lift it from the rotating plate to permit the centrifugal action of the latter to throw the record to one side, and means actuated by said brake mechanism for releasing said trip arm. 100
  4. In combination with a graphophone having a rotating plate, a record thereon, a swinging tone arm, a sound box support pivotally mounted at the outer end of said arm, and means for automatically raising and holding said support, brake mechanism actuated by said tone arm, a spring actuated trip arm, a latch for holding said arm retracted, said trip being adapted to engage the record to partially lift it from the rotating plate to permit the centrifugal action of the latter to throw the record to one side, and a connection between said latch and said brake whereby the latch releases said trip as the brake mechanism moves to operative position. 110
  5. In combination with a graphophone

having a rotating plate provided with a raised portion, a record thereon, a swinging tone arm, a sound box support pivotally mounted at the outer end of said arm, and means for automatically raising and holding said support, brake mechanism actuated by said tone arm, a spring actuated arm extending between said rotating plate and said record, means for holding said arm

retracted, and means for automatically actuating said last mentioned means to release said trip arm to partially lift the record from the rotating plate to permit the centrifugal action of the latter to cause the record to be thrown to one side. 10

In testimony whereof I have signed this specification. 15

ABELARDO HERBERT.
